Des N° 2304

Des. 2304

Post Office of Philadelphia, Pa.

Letters Patent No. 2304. Dated Aug. 1, 1866.

Design for a Tobacco Pipe.

The schedule referred to in these Letters Patent and in this part of the

shall show it, may concern:

Be it known that Louis Franchot of Philadelphia, County of Philadelphia, State of Pennsylvania, has invented or produced a new and original design for a Tobacco Pipe, and I, therefore, declare the accompanying drawing with the following explanation of the same to form a clear and exact description of the said design.

The figure in the accompanying drawing represents a Tobacco pipe.

A is the bowl, and B the stem of the pipe, both of which are connected to the reservoir C.

That portion of the reservoir directly below the bowl, in response to a taper across, while the arm A to which the stem is fitted, is formed in imitation of a branch or stem of a plant, connected to the tree. The root has not been removed.

Explanation.

The design for a tobacco pipe substantially as herein shown and by the accompanying drawing.

John Franchot, Inventor, his design may now be registered in the office of the Commissioner of Patents, his describing witness.
